J C Bookstaver *ATTORNEY.*

UNITED STATES PATENT OFFICE.

BENJAMIN T. ASH, OF BINGHAMTON, NEW YORK.

DESIGN FOR A SPOON.

SPECIFICATION forming part of Design No. 23,689, dated October 16, 1894.

Application filed April 7, 1894. Serial No. 506,789. Term of patent 3½ years.

To all whom it may concern:

Be it known that I, BENJAMIN T. ASH, a citizen of the United States, residing at Binghamton, county of Broome, and State of New York, have invented and produced a new and original Design for Spoons, of which the following is a specification, reference being had to the accompanying drawing, in which the figure is a perspective view of my design.

10 The leading features of my design consist in the representation of a large public building upon the inside of the bowl of the spoon; also an ornamental border upon the handle representing foliage leaves, beginning with

15 the stem near the bowl and separating and running on each edge of the handle, to its

farther end where the two branches are connected by the representation of a shell, the edge of the handle being a continuous line, the foliage turning inward toward the center 20 of the handle and encircling a space upon the handle in which is the representation of a grip sack or satchel.

What I claim as my invention, and desire a patent for, is—

25 The design for a spoon as herein described and shown.

BENJAMIN T. ASH.
